UNITED STATES PATENT OFFICE.

GEORGE H. HAMILTON AND MATTHYS NUBERG, OF GRAND RAPIDS, MICHIGAN,
ASSIGNORS TO AMERICAN SEATING COMPANY, OF GRAND RAPIDS, MICHIGAN, A
CORPORATION OF NEW JERSEY.

DESK AND SEAT STRUCTURE.

Application filed August 21, 1922. Serial No. 583,302.

To all whom it may concern:

Be it known that we, GEORGE H. HAMILTON and MATTHYS NUBERG, citizens of the United States, residing at Grand Rapids, in the county of Kent and State of Michigan, have invented new and useful Improvements in Desk and Seat Structures, of which the following is a specification.

The present invention relates to desk and seat structures; and its object is to provide such a structure having improved means for adjusting the desk or seat portion thereof to a desired height.

This general object and any other more specific objects hereinafter appearing are attained by, and the invention finds preferable embodiment in, the structure herein-after particularly described in the body of this specification and illustrated by the accompanying drawings, in which:

Figure 1 is an end view of a desk and seat structure;

Figure 2 is a sectional view of a portion thereof taken on an approximately vertical plane corresponding to line 2—2 of Figure 1;

Figure 3 is a sectional view (enlarged) of a portion of the same taken on a plane corresponding to line 3—3 of Figure 4;

Figure 4 is a sectional view of the same taken on planes corresponding to line 4—4 of Figure 3;

Figure 5 is a sectional view of the same taken on planes corresponding to line 5—5 of Figure 3;

Figure 6 is a fragmentary view of a retaining piece showing a means for holding the same in position;

Figure 7 is a face view of a rack; and

Figure 8 is a longitudinal sectional view of the same taken on line 8—8 of Figure 7.

In the embodiment of the invention chosen for illustration by the drawings and for detailed description in the body of this specification, a desk and seat structure—such as are employed in school rooms—is shown, having a pair of ends formed preferably of sheet metal and connected by the seat 1, seat-back 2 and desk-top 3. Each of the structure's said ends comprises a supporting member preferably made of a metallic sheet bent to form parallelly disposed sides 4, 4 and an intermediate guide 5 having a rack 6 formed by the uniformly spaced-apart apertures 7; each of the structure's said ends

comprises also a supported member or members—the seat and seat-back sustaining member 8 and the desk-top sustaining member 9. These supported members 8 and 9 are severally movable in an approximately vertical direction on their guides 5 respectively, and each preferably comprises spaced sides 10 having guided portions 11 movable along the opposite sides of the guide 5 and having also slots 12 elongated transversely to the supported member's direction of guided movement. A gear 13 between said sides 10 meshes in its operative position with the rack 6, the teeth of this gear entering the apertures 7 of the rack. This gear has a hub portion 14 rotatable and transaxially movable in the slots 12 and rotatable in rotary bearings 15 in retaining pieces 16, detachably secured to the supported member in such position that the gear is held in operative position (in mesh with the rack) by the rotary bearings 15. These retaining pieces are held in said position by suitable means as by their flanges 17 engaging the guided portions 11 respectively of the supported member. These retaining pieces may be held in said position also by their lugs 18 removably seated in keepers 19 in the sides 10 of the supported member.

It will be understood that in assembling the parts the hub portions 14 are inserted into the slots 12 of the two sides 10, and the guides 5 into the guided portions 11, the hub 14 of the gear 13 being moved to the left hand side of the slots 12 (see Figure 3). The gear may now be turned sufficiently to cause some of its teeth to register with apertures 7 of the rack. The gear being now moved transaxially toward the right hand (see Figure 3), these teeth will be brought into mesh with the rack, in which meshing they will be secured by assembling the retaining pieces 16 held in place by the bolt 22 which also serves to clamp the parts in fixed relation as hereinafter explained.

The supported member may be raised and lowered on the supporting member by turning the gear when in its operative or meshing position (shown in the drawings) by means of a square rod 20 thrust through the squared central openings 21 in the gears; and when raised or lowered to desired position, the supported member may be clamped in such position by the threaded bolt 22

passing through suitable openings in the retaining pieces and through registering openings in the sides 10 of the supported member, said bolt having a nut 23, and also head 5 portion 24 whereby it is held against turning. This same bolt in the construction shown also serves to detachably secure the retaining pieces in position.

It will be seen that the connections between 10 the supporting member and the supported members 8 and 9 are the same and comprise like parts.

In Figures 7 and 8 a modified form of the rack is shown. In these views the metal 15 is slit at 30 and 31 and the upper and lower portions of the metal between such slits is severed in the middle, whereupon the tongues 32, 33 thus formed are bent inwardly, thus providing a more extended surface on which 20 the teeth of the gear or pinion 13 bear in meshing in the apertures 71.

The invention being intended to be pointed out in the claims, is not to be limited to or by details of construction of the particular 25 embodiment thereof illustrated by the drawings or hereinbefore shown or described.

What is claimed is:

1. In a structure of the character described; a supporting member having 30 a guide and a rack; a supported member movable on the guide and having a slot elongated transversely to the supported member's direction of movement; a gear meshing in its operative position with the 35 rack and having a hub portion rotatable and transaxially movable in the slot; a retaining piece having a bearing wherein the hub portion rotates, said piece being detachably secured to the supported member in a 40 position in which the gear is held in its operative position; means for clamping the said members together.

2. In a structure of the character described; a supporting member having a 45 guide and a rack; a supported member movable on the guide and having a slot elongated transversely to the supported member's direction of movement; a gear meshing in its operative position with the rack 50 and having a hub portion rotatable and transaxially movable in the slot; a retaining piece having a bearing wherein the hub portion rotates, said piece being detachably secured to the supported member in a 55 position in which the gear is held in its operative position; means for securing the retaining piece in its said position and for clamping said members together.

3. In a structure of the character de-

scribed; a supporting member having a 60 guide and a rack; a supported member comprising spaced sides having guided portions movable along opposite sides of the guide and having also slots elongated transversely to the supported member's direction of 65 movement; a gear between said sides meshing in its operative position with the rack and having a hub portion rotatable and transaxially movable in the slots; a retaining piece having a bearing wherein the hub portion rotates, said piece being detachably secured to the supported member in a position 70 in which the gear is held in its operative position; means for clamping said sides and the supporting member together. 75

4. In a structure of the character described; a supporting member having a guide and a rack; a supported member comprising spaced sides respectively having guided portions movable along opposite sides of the guide and having also slots elongated transversely to the supported member's direction of movement; a gear between said sides meshing in its operative position with the rack and having a hub portion rotatable and transaxially movable in the slots; retaining pieces having bearings wherein the hub portion rotates, said pieces being detachably secured to the supported member in a position in which the gear is held in its operative position, and said pieces having flanges engaging said sides' guided portions; means for clamping the supporting member, the said pieces and the supported member's said sides together. 90

5. In a structure of the character described; a supporting member of a metallic sheet bent to form parallelly disposed sides and an intermediate guide having spaced apertures forming a rack; a supported member movable on the guide and having a slot elongated transversely to the supported member's direction of movement; a gear meshing in its operative position with the rack and having a hub portion rotatable and transaxially movable in the slot; a retaining piece having a bearing wherein the hub portion rotates, said piece being detachably secured to the supported member in a position in which the gear is held in its operative position; means for clamping the said members together. 100 105 110

In testimony whereof we have hereunto set our hands at Grand Rapids, Michigan, this 12th day of August, 1922.

GEORGE H. HAMILTON.
MATTHYS NUBERG.
